UNITED STATES PATENT OFFICE.

WILLIAM POTTER, OF NEW YORK, N. Y.

WOODWORKING MACHINE.

Application filed June 13, 1922. Serial No. 567,942.

To all whom it may concern:

Be it known that I, WILLIAM POTTER, a citizen of the United States, and residing at New York, in the county of New York 5 and State of New York, have invented certain new and useful Improvements in Woodworking Machines, of which the following is a specification, such as will enable those skilled in the art to which it appertains to make and use the same.

This invention relates to woodworking machines and particularly to machines of this class designed for the purpose of reproducing in a workpiece a predetermined contour from a sample or model and particularly in the reproduction of molding strips, finishing strips and the like, and the object of the invention is to provide a machine of the class and for the purpose specified with means whereby one or more grooves or impressions may be cut in a workpiece to correspond with a predetermined pattern or model; a further object being to provide means for varying the size of the cut in the workpiece to produce a smaller or larger reproduction of the sample or model employed; a further object being to provide means for varying the depth of the cut in the workpiece; and with these and other objects in view the invention consists in a machine of the class and for the purpose specified which is simple in construction and operation and efficient in use and which is constructed and operated as hereinafter described and claimed.

The invention is fully disclosed in the following specification, of which the accompanying drawings form a part, in which the separate parts of my improvement are designated by suitable reference characters in each of the views, and in which:

Fig. 1 is a plan view of my improved machine with part of the construction broken away and in section;

Fig. 2 a front view of the machine as shown in Fig. 1;

Fig. 3 a detail view of a part of the construction shown in Figs. 1 and 2;

Fig. 4 an end view looking in the direction of the arrow 4 of Fig. 1 with part of the construction broken away and in section;

Fig. 4^a is a diagrammatic sectional view showing one method of mounting a workpiece in the machine.

Fig. 5 a partial section on the line 5—5 of Fig. 2;

Fig. 6 is a detail view of a part of the construction shown in Fig. 2 on an enlarged scale and with parts in a different position; and,

Fig. 7 a sectional detail view of a part of the construction shown in Fig. 5 on an enlarged scale.

In practice, I provide a suitable frame structure 10 composed, in the construction shown, of metal tubing or rods joined by elbows and other couplings, said frame being oblong and approximately rectangular in form, comprising four corner standards 11 joined by four front and back longitudinal members 12, and by transverse side members 13, the frame being provided with depending leg members 14 and the standards 11 at the back of the frame being provided with extensions 15 joined by a longitudinal rail 16. Mounted in connection with the rail 16 adjacent to the end rails 13 of the frame are forwardly directed tubular frame members 17 which are free to oscillate or swing and similar frame members 18 are movably connected with a longitudinal rail 19 mounted between the rear standards 11 approximately centrally between the horizontal rear rails 12 as clearly shown in Fig. 5 of the drawing. The end rails 13 at the top of the frame are reinforced by rods 20 which are connected therewith and with the extensions 15 and the rear standards 11, as clearly shown in Fig. 4 of the drawing.

Mounted upon the top of the bottom rails 12 and 13 of the frame is a suitable supporting table 21 and a platform 22 is mounted to move forwardly and backwardly on the table 21, and is keyed in this operation by a key bar 23 as shown in Fig. 2 of the drawing. A similar table 24 is mounted upon the top rails 12 and 13, and a platform 25 is movably mounted on said table, and is keyed thereto by a key bar 25^a also shown in Fig. 2 of the drawing.

Threaded pins 26 are connected with forwardly directed members 18 and extend downwardly through the table member 21, and mounted thereon are springs 27 which normally serve to support the members 18 to hold them in a slightly raised position and similar pins 26 and springs 27 are mounted in connection with the members 17 and cooperate with the table 24 for the same purpose.

A standard 28 is mounted upon the plat-

form 22 centrally thereof and is provided with a forwardly directed arm 29 through which a screw shaft 30 is free to pass, the inner end of said shaft being fixed in the standard 28 as shown at 31 in Fig. 7 of the drawing, and the outer end of said shaft is threaded to pass through and is adapted to cooperate with two threaded jaw members 32 pivotally mounted in connection with a front plate 33 supported in hangers 34 mounted in connection with the upper front rail 12, as clearly shown in Fig. 2 of the drawing. The jaw members 32 are normally held in an inoperative position by a spring 35 as shown in Fig. 6 and are adapted to be moved into operative position and held in such position by pivoted wedge members 36, as clearly shown in Fig. 2 of the drawing, and the operation of the screw shaft by a suitable crank 37, or in any other desired manner, will operate to feed the platform 22 forwardly and backwardly in the frame 10.

Another screw shaft 38 is fixed to the standard 28 as shown at 39 and is in threaded engagement with a hanger 40 mounted in connection with the platform 25 centrally thereof, and the front end of the shaft 38 is free to pass through a bearing 41 in the plate 33, as clearly shown in Figs. 6 and 7, and is provided at its outer end with a knob or handle 42 by means of which the shaft 38 may be rotated. A yoke-shaped device 43 is secured to the forwardly directed arm 29 of the standard 28 and spans the shaft 38 as well as the hanger 40, and the head 44 of which passes over the key bar 25^a secured to the platform 25 and cooperates with a suitable scale 45 mounted upon the bar 26 to indicate the adjustment of the platform 25 independent of the platform 22, as hereinafter described.

It will be understood that the platforms 22 and 25 are of openwork construction as will be apparent upon a consideration of Figs. 1, 4 and 5 of the drawing, and the table member 24 is also preferably provided at its rear end with an extension 46, which forms a support for workpieces which are to be placed transversely or forwardly and backwardly of the machine, and one end of the extension 46 is raised as shown at 47 to form a square against which the workpiece may be placed. In the above operation a strip of wood is preferably placed upon the platform 25 to compensate for the height of the extension 46 to support the workpiece in a substantially level position.

The platform 22 extends approximately the full width of the frame 10 as shown in Fig. 2 of the drawing and adjacent to its ends the top face of said platform is provided with a pair of jaw members 48 between which suitable sample or model

work-pieces 49 may be clamped by screws or bolts 50, and these clamps are located approximately centrally beneath the forwardly directed members 18, whereby gage members 51 mounted in connection with the front ends of the members 18 may operate in connection with the samples or models 49. The gage members 51 are, in the construction shown, in the form of disks rotatably adjustable on the members 18 and provided with a plurality of radially extending gage devices 52 of different forms and constructions, as for example, these gage devices may be V-shaped in form in cross section or arc-shaped in form, or of any other desired shape, and said gage devices are adjustable in the members 51 to regulate the angular position thereof, whenever desired.

The platform 25 is provided at its front end with a work-piece supporting table or member 53, the inner end of which is provided with a longitudinal up-standing shoulder 54 against which a suitable work-piece 55 may be placed, and said flange is preferably provided with prongs 56 adapted to enter the workpiece or the edge thereof, and adjusting clamp rods 57 are imbedded in the table 53 and provided with hook ends 58 adapted to engage the outer edge of the workpiece 55 and are held in position by thumb nuts 59, as clearly shown in Fig. 5 of the drawing.

Two of the clamp rods 57 are employed in the construction shown, but it will be understood that any number of such devices may be employed.

Mounted in connection with the front ends of the members 17 is a rail attaching plate 60 which is of sufficient size to form a substantial and rigid support and is provided with bosses 61 into which the members 17 are passed and secured, and the plate 60 is provided at one end portion thereof and in the top and bottom edges thereof with recesses 62 and 63, and the other end of the plate is beveled and provided with a recess 64, whereby a plane guide rail 65 may be detachably mounted in connection with the plate 60, said rail being provided with screws 66 which are adapted to enter the recesses 62 and 63 and with a screw 67, the shank of which is cut-out as shown at 68 operating in connection with the recess 64 and by means of this construction the rail 65 may be attached and detached to the plate 60 whenever desired.

I also provide a suitable plane 69 which is adapted to be detachably connected with the guide rail 65 and being supported and guided thereon by a channel-shaped member 70 secured to one side face of the stock of the plane 69, as clearly shown in Fig. 5 of the drawing, and the plane 69 is provided with

a suitable handle member 71 by means of which the same may be moved forwardly and backwardly over the rail 65, and the plane employed or the stock or body thereof. 5 is comparatively thin and a triangular or V-shaped cutter blade 72 is preferably employed whereby a substantially pointed blade is provided thus facilitating the cutting of very fine grooves or recesses in a 10 workpiece. Beyond the specific characteristics of the plane herein set out, I am not limited to any specific structure of the plane nor am I necessarily limited to any specific form of cutter blade, and any type of plane 15 suitable for accomplishing the desired result may be employed.

Pivotedly mounted in connection with the members 18 are upwardly directed tubes 73, and threaded rods 74 are adjustably connected 20 with the members 17, said members being provided with spaced apertures 75 to accomplish this result, and the threaded rods 74 are adapted to telescope with the tubes 73 and are adjustable therein and retained 25 in different positions of adjustment by single-winged nuts 76 and double-winged lock nuts 77. The parts 73 and 74 are adapted to limit the movement of the members 17 toward or in the direction of the members 30 18, and when in the position shown in the drawing they serve to link the members 17 and 18 together whereby when the members 18 drop a predetermined distance the members 17 will drop a corresponding distance, 35 but by moving the threaded rods 74 forwardly or backwardly on the members 17, the ratio of movement may be decreased or increased as will be apparent, in other words, the depth of the cut in the workpiece may be 40 greater or less than the depth of the cut in the samples or models 47 employed.

The operation of my improved machine will be readily understood from the foregoing description when taken in connection 45 with the accompanying drawings and the following statement.

It will be understood that the forwardly projecting members 17 and 18 which are movable upon the rails 16 and 19 cooperate 50 with each other through the parts 73 and 74, and when the plane 69 is mounted upon the rail 65, the tool thereof is approximately in the same vertical line as the gage devices 52 on the members 51, as clearly shown in 55 Fig. 5 of the drawing, and by rotating the crank 37 and moving the plane 69 forwardly and backwardly on the rail 65 and over the workpiece 55, the contour of the sample or model 49 will be cut in the workpiece 55 as 60 the screw shaft 30 is rotated in both directions.

At the beginning of the operation of cutting or fashioning the workpiece and in order to rough out said workpiece, the jaw 65 members 32 may be moved into the position

shown in Fig. 6 of the drawing to permit of the free sliding or inward and outward movement of the shaft 30 to correspondingly move both of the platforms 22 and 25, and when the finished cut is desired, the jaw 70 members 32 are moved into operative position whereby a fine adjustment of the platforms 22 and 25 may be obtained.

As hereinbefore set out by adjusting the screw shaft 38 at any time during the above 75 operation the relative positions of the platforms 22 and 25 one with the other may be changed, whereby the contour of the sample or model 49 may be increased or decreased in its production in the workpiece, whenever 80 desired, it being understood that the shaft 38 must be operated while the plane 69 is in operation and intermittently of the feeding or movement of the separate platforms by the shaft 30. The springs 27 normally serve 85 to support the members 17 and 18 to permit of their free operation and the depression of the members 17 in the operation of the plane will correspondingly depress the members 18 and the parts mounted in connection 90 therewith, this operation being accomplished through the tubes 73 and threaded rods 74.

It will be understood that in Figs. 1 and 2 of the drawing, I have shown a very small workpiece as illustrating the method of carrying my invention into effect but, in practice, workpieces of any length may be employed and may be mounted longitudinally of the platform, of the machine, or may be mounted transversely thereof, and I am also not necessarily limited to use of the parts 18, 51 and 52, or the use of the samples or models 49. In other words, the machine may be used for cutting original molding strips or working wood of any form and description, and particularly to the cutting of grooves therein, and while I have shown a frame of specific construction as well as other details of construction for carrying my invention into effect, it will be understood 100 that I am not necessarily limited to the details of construction herein shown and described, nor to the operation of various parts of the apparatus herein set out, and changes 105 therein and modifications thereof may be made, within the scope of the appended claims, without departing from the spirit of my invention or sacrificing its advantages.

In the foregoing reference to the forward and backward mounting of a workpiece on the machine or the transverse mounting of a workpiece thereon, the machine is operated to form transverse grooves in an elongated workpiece in what is known as dado work. In this use of the machine, 120 it will be apparent that the workpiece is moved forwardly and backwardly of the machine in the same manner as in the formation of grooves in a workpiece in forming moldings on a workpiece mounted long- 125 130

itudinally of the machine, but in the first named instance the workpiece may, if desired, be adjusted from time to time especially when a long board or workpiece is employed.

It will also be apparent from the foregoing description taken in connection with the accompanying drawings that a predetermined pattern or patterns may be identically reproduced in a workpiece by rotating the shaft 30 by means of the crank 37 to feed the workpiece supporting table transversely of the plane mounted on the plane supporting means and by manipulating the plane longitudinally of the workpiece or of the machine, and the direction in which the shaft 30 is rotated will govern the movement of the workpiece, and in this operation the shaft is rotated in both directions to move the workpiece back and forth under the plane a number of times until the finished product is produced. It will also be apparent that I may increase or decrease the size of a cut such as a groove or the like in a workpiece in comparison with the size of the corresponding portion of the patterns or samples employed, and in this operation the screw shaft 38 is intermittently adjusted or rotated by the operator while also rotating the shaft 30 to fashion the workpiece in order to vary the relation between the workpiece supporting member and the gage members 51; as for example, in a one inch travel of the gage members 51 over a predetermined pattern, the workpiece supporting table may move a half-inch or two inches or at any other ratio as may be desired.

Having fully described my invention, what I claim as new and desire to secure by Letters Patent, is:—

1. A machine of the class described comprising a suitable workpiece supporting member, means extending longitudinally of said member for supporting a plane there-over and for guiding said plane in its movement, the means for supporting said plane being movable toward and from said member, means for moving said member transversely of the plane supporting means and of the longitudinal movement of said plane, and a model supporting member in operative connection with said workpiece supporting member, and the means for operating the same.

2. A machine of the class described comprising a suitable workpiece supporting member, means extending longitudinally of said member for supporting a plane there-over and for guiding said plane in its movement, the means for supporting said plane being movable toward and from said member, means for moving said member transversely of the plane supporting means and of the longitudinal movement of said plane, a model supporting member in operative

connection with said workpiece supporting member, and the means for operating the same, and means cooperating with said last named member or a model or models mounted thereon for controlling and regulating the movement of the plane supporting means toward and from said workpiece supporting member.

3. A machine of the class described comprising a suitable workpiece supporting member, means extending longitudinally of said member for supporting a plane there-over and for guiding said plane in its movement, the means for supporting said plane being movable toward and from said member, means for moving said member transversely of the plane supporting means and of the longitudinal movement of said plane, a model supporting member in operative connection with said workpiece supporting member, and the means for operating the same, means cooperating with said last named member or a model or models mounted thereon for controlling and regulating the movement of the plane supporting means toward and from said workpiece supporting member, and means for clamping a work-piece on said member.

4. A machine of the class described comprising a suitable workpiece supporting member, means extending longitudinally of said member for supporting a plane there-over and for guiding said plane in its movement, the means for supporting said plane being movable toward and from said member, means for moving said member transversely of the plane supporting means and of the longitudinal movement of said plane, a model supporting member in operative connection with said workpiece supporting member, and the means for operating the same, means cooperating with said last named member or a model or models mounted thereon for controlling and regulating the movement of the plane supporting means toward and from said workpiece supporting member, and means for controlling the ratio of movement between said last named means and the plane supporting means.

5. A machine of the class described comprising a suitable workpiece supporting member, means extending longitudinally of said member for supporting a plane there-over and for guiding said plane in its movement, the means for supporting said plane being movable toward and from said member, means for moving said member transversely of the plane supporting means and of the longitudinal movement of said plane, a model supporting member in operative connection with said workpiece supporting member, and the means for operating the same, means cooperating with said last named member or a model or models mounted thereon for controlling and regulating

- the movement of the plane supporting means toward and from said workpiece supporting member, means for controlling the ratio of movement between said last named means 5 and the plane supporting means, and tensional means for normally supporting both of said last named means.
6. A machine of the class described comprising a suitable workpiece supporting 10 member, means extending longitudinally of said member for supporting a plane thereover and for guiding said plane in its movement, the means for supporting said plane being movable toward and from said member, means for moving said member transversely of the plane supporting means and of the longitudinal movement of said plane, a model supporting member in operative connection with said workpiece supporting 15 member, and the means for operating the same, means cooperating with said last named member or a model or models mounted thereon for controlling and regulating the movement of the plane supporting 20 member, means toward and from said workpiece supporting member, means for controlling the ratio of movement between said last named means and the plane supporting means, tensional means for normally supporting both 25 of said last named means, and means for moving the workpiece supporting member independent of the model supporting member.
7. A machine of the class described comprising a suitable frame, a workpiece supporting member mounted in the frame, a model supporting member mounted in said frame below said workpiece supporting member, means for moving said members 30 forwardly and backwardly of the machine, a plane supporting member mounted in the frame above the workpiece supporting member and movable toward and from the same, gage devices cooperating with said plane supporting member and the model supporting member for controlling the movement of said plane supporting member toward and from said workpiece supporting member. 35
8. A machine of the class described comprising a suitable frame, a workpiece supporting member mounted in the frame, a model supporting member mounted in said frame below said workpiece supporting member, means for moving said members forwardly and backwardly of the machine, a plane supporting member mounted in the frame above the workpiece supporting member and movable toward and from the same, gage devices cooperating with said plane supporting member and the model supporting member for controlling the movement of said plane supporting member toward and from said workpiece supporting member. 40
9. A machine of the class described comprising a suitable frame, a workpiece supporting member mounted in the frame, a model supporting member mounted in said frame below said workpiece supporting member, means for moving said members forwardly and backwardly of the machine, a plane supporting member mounted in the frame above the workpiece supporting member and movable toward and from the same, gage devices cooperating with said plane supporting member and the model supporting member for controlling the movement of said plane supporting member toward and from said workpiece supporting member, and said plane supporting member extending longitudinally of the workpiece supporting member and transversely of the movement thereof, whereby a plane mounted thereon may be moved longitudinally of a workpiece support on said member. 45
10. A machine of the class described comprising a suitable frame, a workpiece supporting member mounted in the frame, a model supporting member mounted in said frame below said workpiece supporting member, means for moving said members forwardly and backwardly of the machine, a plane supporting member mounted in the frame above the workpiece supporting member and movable toward and from the same, gage devices cooperating with said plane supporting member and the model supporting member for controlling the movement of said plane supporting member toward and from said workpiece supporting member, and said plane supporting member extending longitudinally of the workpiece supporting member and transversely of the movement thereof, whereby a plane mounted thereon may be moved longitudinally of a workpiece support on said member, and said gage devices being provided with adjustable heads. 50
11. A machine of the class described comprising a suitable frame and platforms movably mounted in said frame one above another, means for operating both of said platforms forwardly and backwardly of the machine, means for operating one of said platforms independent of the other, and means extending longitudinally of one of the platforms and movable toward and from the same for supporting a plane thereover whereby a plane mounted in connection 55

with said means may be moved and guided longitudinally over said platform and toward and from the same.

12. A machine of the class described comprising a suitable frame and platforms movably mounted in said frame one above another, means for operating both of said platforms forwardly and backwardly of the machine, means for operating one of said platforms independent of the other, means extending longitudinally of one of the platforms and movable toward and from the same for supporting a plane thereover whereby a plane mounted in connection with said means may be moved and guided longitudinally over said platform and toward and from the same, and means for controlling the movement of the plane supporting means toward and from the platform.
13. A machine of the class described comprising a suitable frame and platforms movably mounted in said frame one above another, means for operating both of said platforms forwardly and backwardly of the machine, means for operating one of said platforms independent of the other, means extending longitudinally of one of the platforms and movable toward and from the same for supporting a plane thereover whereby a plane mounted in connection with said means may be moved and guided longitudinally over said platform and toward and from the same, and means for controlling the movement of the plane supporting means toward and from the platform.
14. A machine of the class described comprising a suitable frame and platforms movably mounted in said frame one above another, means for operating both of said platforms forwardly and backwardly of the machine, means for operating one of said platforms independent of the other, means extending longitudinally of one of the platforms and movable toward and from the same for supporting a plane thereover whereby a plane mounted in connection with said means may be moved and guided longitudinally over said platform and toward and from the same, and means for controlling the movement of the plane supporting means toward and from the platform comprising a gage device or devices adapted to operate in connection with a suitable model or models mounted on the other of said platforms.
15. A machine of the class described comprising a suitable frame and platforms movably mounted in said frame one above another, means for operating both of said platforms forwardly and backwardly of the machine, means for operating one of said platforms independent of the other, means extending longitudinally of one of the platforms and movable toward and from the same for supporting a plane thereover whereby a plane mounted in connection with said means may be moved and guided longitudinally over said platform and toward and from the same, and means for controlling the movement of the plane supporting means toward and from the platform comprising a gage device or devices adapted to operate in connection with a suitable model or models mounted on the other of said platforms.

said platforms independent of the other, means extending longitudinally of one of the platforms and movable toward and from the same for supporting a plane thereover whereby a plane mounted in connection with said means may be moved and guided longitudinally over said platform and toward and from the same, means for controlling the movement of the plane supporting means toward and from the platform comprising a gage device or devices adapted to operate in connection with a suitable model or models mounted on the other of said platforms, and means for adjusting the relative position of said plane supporting means and said gage device or devices.

16. A machine of the class described comprising a suitable frame and platforms movably mounted in said frame one above another, means for operating both of said platforms forwardly and backwardly of the machine, means for operating one of said platforms independent of the other, means extending longitudinally of one of the platforms and movable toward and from the same for supporting a plane thereover whereby a plane mounted in connection with said means may be moved and guided longitudinally over said platform and toward and from the same, means for controlling the movement of the plane supporting means toward and from the platform comprising a gage device or devices adapted to operate in connection with a suitable model or models mounted on the other of said platforms, and means for adjusting the relative position of said plane supporting means and said gage device or devices, and tensional means for normally supporting the plane supporting said gage device or devices.

In testimony that I claim the foregoing as my invention I have signed my name this 10th day of June, 1922.

WILLIAM POTTER.
